UNITED STATES PATENT OFFICE.

SAMUEL BIENENZUCHT, OF NEW YORK, N. Y.

DESIGN FOR A WATCH-FOB.

41,284.

Specification for Design.

Patented Apr. 4, 1911.

Application filed November 26, 1910. Serial No. 594,416. Term of patent 7 years.

To all whom it may concern:

Be it known that I, SAMUEL BIENENZUCHT, a citizen of the United States, residing in the city of New York, borough of Manhattan, in the county and State of New York, have invented a new, original, and ornamental Design for a Watch-Fob, of which the following is a specification, reference being had to the accompanying drawing, forming part thereof.

The figure is a perspective view of a watch fob showing my design.

I claim:

The ornamental design for a watch fob as shown.

SAML. BIENENZUCHT.

Witnesses:

ABRAHAM BIENENZUCHT,
WILLIAM PROKOCIMER.
